UNITED STATES PATENT OFFICE.

JOSEPH S. DUNCAN, OF CHICAGO, ILLINOIS, ASSIGNOR TO ADDRESSOGRAPH COMPANY,
OF CHICAGO, ILLINOIS, A CORPORATION OF ILLINOIS.

PRINTING DEVICE.

1,096,495.

Specification of Letters Patent. Patented May 12, 1914.

Application filed August 26, 1912. Serial No. 716,988.

To all whom it may concern:

Be it known that I, JOSEPH S. DUNCAN, a citizen of the United States, residing at Chicago, in the county of Cook and State of Illinois, have invented certain new and useful Improvements in Printing Devices, of which the following is a specification.

My invention relates to printing devices, and has for its primary object the provision 10 of a device suitable for printing on circular letters the address and salutation disposed in proper relation and spaced the requisite distance from the body of the letter.

Another object of the invention is to provide 15 a novel printing device bearing the address and salutation and also designed to carry on its front face a data card being the desired information regarding the device by which the same may be identified when the 20 devices are arranged in a drawer in accordance with a card-index system.

A further object is to provide a device of this character which will present a flat front face on which the printing characters are 25 formed and which will have on its rear face suitable spacing flanges to facilitate sidewise withdrawal of one of the devices from a stack without engagement with or obstruction by adjacent devices.

30 In the accompanying drawings illustrating a preferred embodiment of the invention—Figure 1 is a front view of my improved printing device; Fig. 2 is a rear view thereof; Fig. 3 is a longitudinal sectional view on the line 5—5 of Fig. 1; and Fig. 4 is a transverse sectional view on the line 6—6 of Fig. 2.

The printing device as shown in the accompanying drawings is preferably stamped 40 from a single sheet of metal and comprises a flat portion 12 of suitable dimensions to accommodate several lines of printing characters which are perfectly stamped up thereon from the body of the metal. The 45 address, which may consist of several lines of printing characters, is arranged on the front face of the flat portion of the device as it is desired that it should appear on the completed form letter. The salutation 50 which is shown in the present instance, as the word "Gentlemen", is also stamped up on the flat portion of the plate and on the front face thereof and closely adjacent the

lower edge of the device, so that when the address form and a printing form are in 55 coöperative printing relation the salutation will be spaced the requisite distance from the first line of the body of the letter. In order to strengthen the address form longitudinally, the edge of the metal from the salutation to the opposite end of the device is turned back flat against the back face of the device to form a strengthening rib 13, as best shown in Fig. 2. At the ends of the device the metal is folded back upon itself and 60 then bent downwardly to produce the spacing flanges or ribs 14 (Figs. 2 and 3) which serve to separate the devices when they are nested or stacked in a drawer or magazine and prevent the faces of the printing characters from becoming injured by contact 65 with the adjacent devices.

A depressed panel 15 is formed adjacent the opposite edge of the plate from the salutation to receive a data-bearing card 16 75 which is slid into the panel from one end. The longitudinal edge of the material outside the panel is folded forwardly to form a flange 17 partially overlying the panel beneath which the card 16 is inserted, this 80 flange being adapted to hold the upper edge of the card in position. In the formation of the panel the material is cut so as to provide lips 18 projecting over the panel and arranged to overlie the lower edge of the card 85 16 to hold the card in position. The flange 17 is pressed down flat against the body of the metal so that its front face lies in a plane with the character-bearing portion 15 and also in the plane of the front face of the ends 90 of the device. One end of the flange 17, as best shown in Fig. 1, is partially cut away as indicated at 19 to permit the insertion of the card beneath the flange. At the opposite end the flange overlies the margin of the 95 plate, and sufficient pressure is exerted thereon when the plate is being formed to depress it into the body of the metal so that its front face lies flush with the margin. A shoulder 21 is formed from the body of the metal 100 adjacent the left end of the device, viewing Fig. 1, and at the end of the card-receiving panel to prevent longitudinal displacement of the card after it has been positioned in the panel. When it is desired to remove the 105 card for any purpose the end adjacent the

shoulder is lifted up over the shoulder whereupon the card may be readily withdrawn.

The depressed panel 15 is provided at its top and bottom with openings 22 and 23, respectively. I prefer to remove the metal entirely in forming the openings 22, but in forming the openings 23 the metal is left in its original plane as previously described to provide the lips 18. The openings 22 and 23 are arranged in pairs one above the other and, as many pairs may be provided extending lengthwise of the panel, as is desired. One or more designation tabs 24 provided with a stem adapted to be projected through the openings 22 and 23 may be used, whereby the tab is retained in position.

The combined address and salutation devices are adapted to be stored in a drawer or tray and deposited in a magazine for use, from which they are conveyed by any suitable mechanism into printing position adjacent the stationarily mounted letter form. The data card and the index tab carried by each printing device enables any particular one to be selected from the storage tray and to be removed or replaced by another device, or the information on the data card may be changed or the card may be removed and replaced by a new card if desired. The address and salutation are so arranged on the devices that when a device is positioned in co-operative relation with the letter form the salutation is spaced the requisite distance from the first line of the body of the letter, and the address, salutation and the body of the letter may be printed simultaneously at one operation. It will be observed that the front of each printing device is substantially flat, and that the character bearing portion and all of the margins of the front of the device are disposed in a common plane. The longitudinally extending strengthening strip 13 at the back of the device is folded flat against the body of the metal, and the spacing flanges or ribs 14 project a sufficient distance from the back to prevent engagement between this flat strengthening strip and the printing faces of the characters of contiguous devices when they are stacked or nested, and also enable any particular device to be removed laterally from the stack without engagement with or interference by the adjacent devices. It is believed my invention will be understood from the foregoing without further description, and it will be obvious that the details of construction shown and described may be varied within considerable limits without departing from the scope of the invention as set forth in the following claims.

I claim:

1. A sheet metal printing device, comprising a flat character-bearing portion, and a depressed card-receiving panel at one side

thereof, the front face of the character-bearing portion and the faces of the margins entirely around the periphery of the device being all disposed in a common plane, one longitudinal margin comprising an edge 70 of the metal folded forwardly to provide a flange overlying said depressed panel.

2. A sheet metal printing device, comprising a flat character-bearing portion, and a depressed card-receiving panel at one side 75 thereof, the front face of the character-bearing portion and the entire peripheral margins of the device being all disposed in a common plane, one longitudinal margin comprising an edge of the metal folded 80 forwardly to provide a flange overlying said depressed panel, the metal at the opposite side of the device being folded rearwardly to provide a strengthening rib at the back of the device.

3. A sheet metal printing device, comprising a flat character-bearing portion, and a depressed card-receiving panel at one side thereof, the front face of the character-bearing portion and the front faces of the 90 margins around the periphery of the device being all disposed in a common plane, one longitudinal margin comprising an edge of the metal folded forwardly to provide a flange overlying said depressed panel, the 95 metal ends of the device being folded rearwardly and formed to provide spacing ribs on the back of the device.

4. A sheet metal printing device comprising a character-bearing portion lying in the 100 plane of the body of the device, a card-receiving panel depressed in the device adjacent the character bearing portion, a flange partially overlying said panel at one edge of the device, the front face of said flange 105 being disposed in the plane of the character-bearing portion, and a shoulder formed at one end of the panel to prevent longitudinal displacement of the card disposed therein.

5. A sheet metal printing device having 110 a card-receiving panel depressed in the front face thereof, the margins and the front face of the device being in the same plane, one longitudinal edge of the device being folded over across the front of the plate in the 115 plane of said front and overhanging the depressed panel, the opposite longitudinal edge of the device being folded over across the back of the device to strengthen the same, and transversely extending spacing flanges on the back of the device, there being printing characters stamped up on the front face of the device at one side of the card-receiving panel.

6. A sheet metal printing device presenting a flat front face upon which are formed a plurality of printing characters, a portion of said face being depressed to provide a card-receiving panel, transversely extending spacing flanges formed at the ends of the 120 125 130

device on the back thereof, a portion of one longitudinal edge of the device being folded back flat against the rear face of the character-bearing portion to form a strengthening strip of minimum thickness, the spacing flanges projecting a sufficient distance to permit the device to be withdrawn from a

stack without engagement between said strengthening strip and the printing characters of an adjacent device.
